UNITED STATES PATENT OFFICE.

THOMAS JOHN WOODWARD, OF WEST BROMWICH, ASSIGNOR TO CHANCE BROTHERS & CO., LIMITED, OF WEST SMETHWICH, ENGLAND.

DESIGN FOR PLATE-GLASS.

SPECIFICATION forming part of Design No. 23,935, dated January 1, 1895.

Application filed November 16, 1894. Serial No. 529,054. Term of patent 7 years.

To all whom it may concern:

Be it known that I, THOMAS JOHN WOODWARD, designer, a subject of the Queen of Great Britain, residing at No. 60 Barrow 5 Street, West Bromwich, in the county of Stafford, England, have invented and produced a new and original Design for the Ornamentation of Plate-Glass, of which the following is a specification, reference being had to the accompanying drawing, forming part thereof.

The accompanying drawing represents the face of a piece of plate glass ornamented with my design, and also a cross section of the same taken on the line *p, p*.

15 This design is composed of a series of groups of flower ornaments of the chrysanthemum

type, each group consisting of a fully opened central flower *a* surrounded by other partially opened flowers and leafages *b*, the stems of the outer or encircling flowers springing 20 from the central flower *a* in the manner shown. The whole pattern is in low relief and a cross section as shown consists of a series of angles or zig-zags except at the central flower *a* where it is concave and in the lowest plane. 25

What I claim is—

The design for plate glass, substantially as herein shown and described.

THOMAS JOHN WOODWARD. [L. s.]
